UNITED STATES PATENT OFFICE.

KARL ALQUIST, OF SCHENECTADY, NEW YORK.

GEARING.

1,334,008.

Specification of Letters Patent. Patented Mar. 16, 1920.

Application filed January 16, 1918. Serial No. 212,029.

To all whom it may concern:

Be it known that I, KARL ALQUIST, a subject of the King of Sweden, residing at Schenectady, in the county of Schenectady,

5 State of New York, have invented certain new and useful Improvements in Gearing, of which the following is a specification.

The present invention relates to gearing of the single reduction type wherein a pinion 10 drives a low speed gear wheel through two intermediate gear wheels which transmit the load in parallel. The pinion is usually balanced between the two intermediate gear wheels, which in turn mesh 15 with the driven gear wheel.

In a gearing of this type the strain on the teeth and the wear of the tooth surface is much greater between the pinion and the intermediate gear wheels than it is between 20 the intermediate gear wheels and the low speed wheel. This is at once apparent from a consideration of the diameters of the respective wheels. Owing to the small diameter of the pinion there is not the same 25 extent of contacting surface between it and the intermediate gear wheels that there is between the intermediate gear wheels and the low speed wheel, and also the teeth of the pinion are more curved. As a result the 30 output of a gearing of this type is limited to that which can be transmitted between the pinion and the intermediate gear wheels, while the teeth of the intermediate gear wheels engaging the low speed gear wheel 35 could easily carry a much larger load both with reference to wear and strength of the teeth. The result is, therefore, that the pinion is the only member of the gear train which is working to capacity.

40 It is always desirable in a gearing that all parts, so far as possible, do the maximum work of which they are capable; *i. e.*, that all parts be loaded to the same extent in regard to stresses, as this means the highest output with the lowest weight. This is important, not only as concerns the cost of manufacture, but also is often of primary importance in connection with the use to 45 which the gearing is to be put. For example, in the case of ship propulsion, it is very important that the gearing, as well as the other machinery, be as light as possible.

50 The object of the present invention is to provide an improved structure and arrangement in a gearing of the type referred to above wherein the gearing members will be

much more nearly loaded to the same extent, and for a consideration of what I believe to be novel and my invention, attention is directed to the accompanying specification 60 and the claims appended thereto.

In the drawing, Figure 1 is a side elevation of a gearing embodying my invention, and Fig. 2 is a diagrammatic end view 65 thereof.

Referring to the drawing, the central portion of Fig. 1 shows the known arrangement of this type of gearing wherein a pinion 5 carried by a shaft 6 drives a low speed gear wheel 7 located on a shaft 8, through two intermediate gear wheels 9 and 10 carried by shafts 11 and 12 respectively. The pinion 5 is balanced between the gear wheels 9 and 10 and such gear wheels transmit the load in parallel from the pinion 5 to the 75 low speed gear wheel 7.

Now as already stated, the limiting member as to output of such a known type of gearing is the pinion 5, the intermediate gear wheels 9 and 10 being capable of transmitting a much greater load to the low speed wheel 7 than that which the pinion can transmit to them. According to my invention, therefore, I provide additional means for supplying power directly to the intermediate gear wheels 9 and 10 independently 80 of the pinion 5, and to this end I extend the ends of the pinion shaft 6 and mount thereon pinion members or parts 13, 13^a, which mesh with intermediate gear wheels or gear 85 wheel parts 14, 14^a, and 15, 15^a mounted on extensions of shafts 11 and 12 respectively. The shaft extensions may be an integral 90 part of the shafts, as shown in the case of shafts 11 and 12, or such extensions may be 95 formed separately and coupled to the shaft, as shown in the case of the pinion shaft 6. With this arrangement, it will be seen, additional power will be transmitted from shaft 6 to intermediate gear wheels 9 and 10 100 by means of the pinion members 13, 13^a and gear wheel members 14, 14^a, 15, 15^a, and as a result the gearing can be so designed that all the driving lines between the gear wheels 105 are properly loaded.

The gearing illustrated is of the double helical or herringbone type and the pinion parts 13, 13^a and intermediate gear wheel parts 14, 14^a and 15, 15^a are shown as having tooth structures which are a continuation of the tooth structures of the adjacent halves of the pinion 5 and intermediate 110

gear wheels 9 and 10. However, it will be understood that I am not limited to this arrangement.

The intermediate gear wheels 9 and 10 and the intermediate gear wheel parts 14, 14^a, 15 and 15^a are shown as being of the flexible type invented by me which comprises a plurality of plates or disks rigidly mounted on a suitable support and slightly spaced apart at their outer edges to permit of slight axial yielding under tooth pressures. Such a gear wheel is disclosed in my Patent No. 1,165,830, dated December 28, 1915, and while I prefer to use it, it is to be understood that my invention is not limited thereto.

The respective shafts 6, 8, 11 and 12 are provided with suitable bearings 16, the shaft 6 being provided preferably with four such bearings, and the remaining shafts with two each, the intermediate gear wheel parts 14, 14^a, 15 and 15^a being overhung on the ends of shafts 11 and 12. This means that only two additional bearings; viz., those at the ends of shaft 6 need be provided over the number required for the gearing of the known type referred to. The additional cost, therefore, is not great as compared to the added power which the improved gearing arrangement will transmit.

The pinion members 13 and 13^a and the gear wheel parts 14, 14^a and 15, 15^a are shown as being spaced some distance from the pinion 5 and intermediate gear wheels 9 and 10 to accommodate bearings between them, the gear wheel parts 14, 14^a, 15 and 15^a being overhung on their respective shafts. It will be understood, however, that they need not be thus spaced apart, but may be brought closer together, if found desirable, and in fact may be made as an integral part of the pinion 5 and gear wheels 9 and 10.

A pinion drive, as shown in Fig. 1, may be provided on only one side of the gear wheel 7, or it may be duplicated on the opposite side, as indicated at A and B in Fig. 2. This latter arrangement is found advantageous for example, in ship propulsion, where it is desired to utilize two prime movers to drive a single propeller shaft.

In accordance with the provisions of the patent statutes, I have described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is:

1. In combination, a high speed shaft, a low speed shaft, gearing through which

power is transmitted from one to the other, said gearing comprising a pinion on the high speed shaft, a gear wheel on the low speed shaft, and a gear wheel which runs at a speed intermediate between that of the two shafts, and meshes directly with the pinion and first named gear wheel, and means for transmitting power from the high speed shaft directly to said intermediate gear wheel independently of said pinion.

2. In combination, a high speed shaft, a low speed shaft, gearing through which power is transmitted from one to the other, said gearing comprising a pinion on the high speed shaft, a gear wheel on the low speed shaft, and a gear wheel which runs at a speed intermediate between that of the two shafts and meshes directly with the pinion and first named gear wheel, and additional gearing means which transmits power from said high speed shaft to said intermediate gear wheel independently of said pinion.

3. The combination with a gearing comprising a shaft, a high speed pinion thereon, a low speed gear wheel, and two intermediate gear wheels which mesh with the pinion and low speed gear wheel and transmit power from one to the other, of means for supplying power from said shaft to the intermediate gear wheels independently of said pinion.

4. The combination with a gearing comprising a shaft, a high speed pinion thereon, a low speed gear wheel, and two intermediate gear wheels which mesh with the pinion and low speed gear wheel and transmit power from one to the other, of means independent of the pinion for supplying additional power to both the intermediate gear wheels.

5. In a gearing, the combination of a low speed gear wheel, intermediate gear wheel means having portions which mesh directly with the low speed gear wheel and portions which do not, and a shaft having pinion means thereon which mesh directly with all the portions of said intermediate gear wheel means.

6. In a gearing, the combination of a low speed gear wheel, flexible gear wheel means having portions which mesh with the teeth of said low speed gear wheel and portions which are not in mesh therewith, and pinion means which mesh directly with said flexible gear wheel means over their entire axial length.

7. In a gearing, the combination of a shaft carrying pinion means, a low speed gear wheel, and two intermediate gear wheel means which mesh directly with said pinion means and said low speed gear wheel and transmit the load in parallel from one to the other, said low speed gear wheel hav-

ing a driving face of less axial width than that of the pinion means and intermediate gear wheel means.

8. The combination with a gearing comprising a shaft, a high speed pinion thereon, a low speed gear wheel, and two shafts carrying intermediate gear wheels which mesh with the pinion and low speed gear wheel and transmit power from one to the other, of meshing gear wheel members mounted on extensions of said pinion and intermediate gear wheel shafts which serve to transmit power directly to said intermediate gear wheel independently of said pinion.

9. The combination with a gearing comprising a shaft, a high speed pinion there-

on, a low speed gear wheel, and two shafts carrying intermediate gear wheels which mesh with the pinion and low speed gear wheel and transmit power from one to the other, of meshing gear wheel members mounted on extensions of said pinion and intermediate gear wheel shafts which serve to transmit power directly to said intermediate gear wheels independently of said pinion, said intermediate gear wheels and the gear wheel members mounted on the extensions of the intermediate gear wheel shafts being flexible.

In witness whereof, I have hereunto set my hand this 14th day of January, 1918.

KARL ALQUIST.
